UNITED STATES PATENT OFFICE.

FLETCHER SCHAUM, OF PHILADELPHIA, AND CARL SCHAUM, OF WYNCOTE, PENNSYLVANIA, ASSIGNORS TO FLETCHER WORKS, OF PHILADELPHIA, PENNSYLVANIA, A CORPORATION OF PENNSYLVANIA.

LIQUID DISPENSER.

Application filed June 13, 1927. Serial No. 198,525.

Our invention relates to a new and useful improvement in liquid dispensers, and more particularly to a dispenser that is to be used in conjunction with a clothes washing machine.

In the large washing machines used in commercial laundries, different arrangements are provided for intermittently feeding different materials and liquids to the washing machine, such as soap, bluing, sour, and bleaching liquids, all of which materials and liquids remain in the clothes washer for only a certain length of time. The washer is then flushed or emptied so that fresh batches of water and liquids and other materials may be added.

The present invention provides a means for dispensing a predetermined amount of liquid to the washer and to further provide means whereby there will be no continuous or intermittent drip between the feedings of the liquid to the washer.

Still another object of the invention is to provide a dispenser that is intermittently and automatically operated, the present invention having to do with the actual dispensing mechanism and the manner in which it is arranged so that when the automatic mechanism operates for tripping the dispenser, the dispenser will feed and then drop back a predetermined distance, so that there will be no dripping of the liquid between its operations.

The actual means for operating the above mechanism, that is, the means for applying the power at stated intervals to this mechanism forms the subject matter of a separate application.

Still another object of the invention is to provide a simple liquid dispensing mechanism that will feed a predetermined amount of liquid to the washer, and at the same time will prevent any drip between or after each of the dispensing movements.

With these and other objects in view, the invention consists in certain new and novel arrangements and combination of parts as will be hereinafter more fully described and pointed out in the claims.

Referring now to the drawings, showing a preferred embodiment of our invention,

Fig. 1 is a side elevation showing the

ratchet movement for operating the bucket, the bucket being shown in section.

Fig. 2 is a front elevation of the mechanism shown in Fig. 1, and

55

Fig. 3 shows a slightly modified form of ratchet movement for operating the bucket.

Referring now more specifically to the several views, there is shown a bucket or tank 1, having approximately the shape of a quadrant. This bucket or tank may be a casting or may be formed of thin sheet metal, and provided with metal ribs 2, there being formed a slot or bearing 3 at the center of the radii of the bucket. This bearing is provided with the overhanging lip 4 so that as the bucket is oscillated about an axial shaft 5, it will always be pivotally and centrally supported.

This shaft 5 will be supported in the arms 6 which are shown fragmentarily in Fig. 2, these arms, of course, being long enough to permit an oscillation of the bucket about the axial shaft 5.

This bucket is preferably provided with a lug 7 at the lower edge of its front or vertical face, so that a small rope or cable 8 may pass around the arcuate portion and be fastened at its upper end about the small drum 9, which in turn is fixedly secured on the small shaft 10 mounted in the frame 11, which frame is also shown fragmentarily.

To the other end of this shaft 10 is loosely mounted the upright arm 12 provided with the slot 13 in its upper end in which slot there may be movably bolted a hook or eyelet 14 to which, in turn, will then be secured a rod or rope 15 which is adapted to extend to a power mechanism for intermittently pulling and releasing this rope 15 to in turn move the arm 12 and let it return.

In another application there is shown and described the means for intermittently operating this cable or rod 15, it being sufficient in this application to state that at timed intervals a pulling force is applied to this cable 15.

By providing the slot 13 and the securing means 14 within the slot, the length of the throw of the arm 12 may be regulated within certain limits.

Referring again to the arm 12, there will

be seen a small lug 16 to which there is pivoted a small actuating pawl 17 which in turn is designed to cooperate with the teeth 18 on a ratchet wheel 19 which wheel is fixedly mounted on the shaft 10.

In Fig. 2 there will be seen secured to the eyelet or hook 14 and to the rear of the cable 15, a small spring 20 which in turn is fastened indirectly to the frame 11, so that the 10 arm 12 will normally be held in a rearward or retracted position.

As far as the specification has proceeded, it will be seen that a pull on the cable 15 will advance the arm 12 from its retracted position to the upright position shown in full lines in Fig. 1, and the pawl 17 engaging one of the teeth 18 will advance the ratchet wheel 19 to revolve the drum and thus slightly raise the bucket 1.

20 It is to be understood that the length of movement of the cable 15 will be predetermined as well as the throw of the arm 12, so that a movement or pull on the cable 15 will advance the arm 12 and revolve the ratchet a 25 predetermined amount.

Means have to be provided, however, to prevent any drip from the bucket after each operation, as otherwise the water level would always be just even with the mouth of the 30 bucket and would continue to drip, especially with any jarring of the machine, and this would be a disadvantage as at certain times it would not be desired to have any of the liquid from this dispenser, whatever it may be, dropping from this bucket into the washing machine.

We have, therefore, provided means whereby the bucket is oscillated or raised a predetermined amount, so that the liquid, that is, 40 a certain amount, will spill out of the same after which the bucket is allowed to swing back slightly, so that the water level in the tank will be slightly below the mouth of the bucket.

45 To accomplish this, we provide a second pawl 21 (holding pawl) which is held in contact with the ratchet teeth by the spring 22 as may be seen in Fig. 1.

The size of the ratchet teeth 18 is in a certain ratio with the throw of the arm 12 and the disposition of the pawl 21 is such that as the arm 12 moves forwardly when operated, it will advance the ratchet wheel one and three-fourths teeth. The pawl 21 is so disposed that it will come to rest on the slope of a tooth rather than against the face of the tooth and the weight of the tank on the drum will cause the ratchet wheel to slip rearwardly until the pawl 21 engages the face of the oncoming tooth. This slip is practically three-fourths of the length of the tooth. In other words, on each movement or throw of the arm 12, the ratchet wheel will slip back the distance of three-fourths of a tooth.

From this it will be seen that the bucket or container will be elevated a slight distance to spill a predetermined amount of liquid, after which spilling the bucket will drop a slight distance, that is, a distance in proportion to the slip for three-fourths of the length of a 70 tooth.

Eventually the drum 9 will wind up enough of the cable to empty the bucket or container, after which, of course, it will again be reset and filled with the desired liquid.

It will also be seen that as the bucket revolves a predetermined amount about the axis 5, and as the shape of the bucket is a quadrant, the same amount of liquid will be dispensed each time, regardless of how full 80 the bucket is or what its position.

The water level, right after the dispensing movement, will be slightly below the mouth of the bucket, so that there will be no drip between operations.

85 In Fig. 3 we have shown a slightly modified form for elevating the bucket in a step by step movement and also to allow the bucket to lower slightly immediately after its elevation, so that the water level with this form of operating mechanism will always be slightly below the mouth of the bucket between the dispensing operations, and therefore prevent any undesirable dripping.

90 In this form, the bucket and drum are the same, but the ratchet wheel 23 may be provided with slightly smaller teeth 24 than in the wheel 19. The same kind of operating lever or arm 25 is shown loosely mounted on the shaft 10. There is also a pawl 26 attached to this arm, and likewise a slot 27 is shown in which there is a bolt 28 to which is fastened the cable 29 and to which is also fastened a small spring 30. The throw, therefore, can be regulated by securing the bolt 28 at a different position up and down the slot 27.

100 Now, the holding pawl 31 is slightly different from the holding pawl 21 in that it is provided with a slot 32 at its lower end so that it may ride as well as pivot on the pin 33. This pawl has the tooth 34 to engage the ratchet teeth 24, and is provided with the small arms 35 on its end to straddle the ratchet wheel 23 so that the pawl will never slip off the wheel 23.

110 As before mentioned, the ratchet wheel and drum are fixedly secured on the shaft 10 so that an operation of the cable 29 by a mechanism (not shown) will advance the arm 25 and move or revolve the ratchet wheel the 120 length of the stroke of the arm. This will elevate the bucket a predetermined amount through the cable 8, but instead of the pawl 31 slipping over a tooth as in the former instance, it will immediately engage one of the teeth 24 and as soon as the cable 29 is released so that the arm 25 swings backwardly, it will 125 allow the ratchet wheel to slip back the length

of the slot 32 in the pawl 31, where, of course, it will hold the ratchet from the further movement.

Thus, it will be seen that every time the cable 29 is operated, it will raise the bucket a slight amount, rather revolve the bucket a slight amount, to thus spill or dispense an amount of liquid, after which the bucket will slip back a slight distance so that the water level is again below the mouth of the bucket and will prevent any undesired dripping.

From the foregoing it will be seen that we have provided a dispensing mechanism for liquids to be fed into a washing machine, and whereby a certain amount is fed at predetermined times, also wherein the amount fed is always the same. At the same time, however, there is no chance for any dripping between the operations, which dripping might spoil the proportions of the various liquids or chemicals in the washer.

It will also be seen that the action is positive; that the mechanisms are not complicated, and the device is one that may be quickly assembled and readily operated.

The bucket might be of other desired shape, just so it performs the same functions in the same manner.

Many slight changes might be made without in any way departing from the spirit and scope of the invention.

Having thus described our invention, what we claim as new and desire to secure by Letters Patent is:—

- 35 1. A liquid dispenser for clothes washing machines comprising a triangular-shaped pivotal bucket, means for pivoting the bucket at the apex of the triangle, a ratchet mechanism cooperatively connected with said bucket for progressively tilting the bucket, said mechanism also arranged to allow the bucket to drop back a fractional part of its step by step elevation.
- 40 2. A liquid dispenser comprising an oscillating bucket of triangular shape, pivoted at its upper edge, a cable secured to said bucket, a frame independent of the bucket, a shaft mounted in said frame, a drum and ratchet mounted on said shaft, a loosely mounted arm on said shaft, a moving pawl and a holding pawl cooperating with the ratchet, an arm for moving said first mentioned pawl, the arrangement of the two pawls and ratchet being such that the bucket is elevated in a step by step movement and dropped back at each operation a portion of its elevation.
- 45 3. A liquid dispenser for clothes washing machines, comprising a tilting bucket, a drum mounted above said bucket, a cable from the drum to the bucket, means for progressively rotating the drum in a step by step movement to progressively tilt the bucket and means for slipping the drum for
- 50 a fractional part of its winding movement after each rotating movement.
- 55 4. In combination with a pivotally supported bucket, a drum and means connecting the drum with the bucket, means for rotating the drum in a step by step movement to elevate the bucket, the weight of the bucket causing the drum to normally slip back, means limiting the said slip to a part of the step by step movement, whereby the liquid level of the bucket is below the level of the mouth of the bucket during the interval between the successive step by step tilting movements.
- 60 5. A liquid dispenser device comprising a pivoted bucket, a drum cooperatively connected to said bucket, means for progressively winding up the drum in a step by step movement to tilt the bucket, the weight of the bucket causing the drum to normally slip back at the end of each step by step movement and means for limiting the slip of the drum to a fractional part of its progressive movement.
- 65 6. In a dispensing machine for liquids, an arcuate bucket pivotally supported at one end, a cable attached to said bucket, a drum having the said cable attached thereto, a loosely mounted ratchet wheel cooperating with said drum, and an operating arm connected with said wheel, a pawl on said arm for advancing the ratchet wheel to elevate the bucket in a step by step movement, the weight of the bucket causing the drum to normally slip back and a second pawl so disposed as to limit the ratchet to slip back three-quarters of a tooth on the completion of the operation of the said operating arm.
- 70 7. A liquid dispenser for clothes washing machines comprising a tiltable bucket, a drum cooperating with the bucket, a rotatable means connected with the drum whereby the drum is partially rotated and the bucket is successively tilted a predetermined amount, the weight of the said bucket causing the bucket and the drum to normally slip back after each tilting operation and means for limiting the amount of slip to a fractional amount of the partial rotation of the drum.
- 75 8. A liquid dispenser comprising a tilttable arcuate-shaped bucket and a cable secured to the lower edge of said bucket, in combination with a shaft and a drum and a ratchet wheel mounted on said shaft, a loosely mounted arm on said shaft, and means connected with said arm whereby when said arm is operated, the ratchet wheel is drawn through a number of teeth to rotate the drum and partially elevate the bucket, the weight of the bucket normally causing the drum to unwind and further means connected to the ratchet wheel to limit the amount of unwinding of the drum to a fractional amount of the preceding winding of the drum, whereby the said liquid level

in the bucket between said operations is below the mouth of the bucket.

9. A liquid dispenser comprising a pivotally supported tiltable bucket, a frame, a drum and ratchet wheel mounted in said frame, the drum and bucket being connected and the ratchet wheel fixed with relation to the drum, an operating arm, a pawl on said arm for engaging said ratchet, a spring for holding the arm in a retracted position, said arm adapted to be intermittently moved forward, a second pawl for holding the ratchet wheel against movement while the arm is being completely retracted and for slipping the ratchet wheel a definite amount after the start of the retracted movement of the arm whereby the liquid level of the bucket between said operations is below the mouth of the bucket.

20 10. A liquid dispenser comprising an angular-shaped pivotal bucket, means for pivoting the bucket at its apex, means cooperating with the bucket for progressively tilting the same, means for dropping the bucket 25 back a fractional part of each progressive

tilting, whereby the liquid level of the bucket is below the level of the mouth of the bucket after each progressive tilting of the bucket.

11. A liquid dispenser comprising a tilting bucket and a drum operable with said bucket, a ratchet wheel fixedly mounted with relation to the drum, an arm loosely mounted with relation to the ratchet and provided with a pawl for engaging the ratchet to revolve said drum and tilt the bucket, a spring for normally holding the arm in a retracted position, means for varying the stroke of the arm, means for holding the ratchet while the arm is being retracted and said last mentioned means arranged to slightly slip the ratchet wheel in a rearward direction, after the arm is operated so that the liquid level of the bucket will be below the mouth of the bucket at the end of each tilting operation.

In testimony whereof we affix our signatures.
